ATTORNEYS.

UNITED STATES PATENT OFFICE.

FREDERICK C. BAUER, OF PHILADELPHIA, PENNSYLVANIA.

TOY CAR.

1,416,775.

Specification of Letters Patent. Patented May 23, 1922.

Application filed January 14, 1922. Serial No. 529,168.

To all whom it may concern:

Be it known that I, FREDERICK C. BAUER, a citizen of the United States, residing in the city and county of Philadelphia, State 5 of Pennsylvania, have invented a new and useful Toy Car, of which the following is a specification.

My invention consists of a toy car which is adapted to run on a curved track having the axles of its wheels mounted on 10 bearings which permit said axles to slide or give on the pedestals of the car which form said bearings so as to compensate for the curvature of the rails comprising the track 15 and thereby preventing the wheels from binding on the rails and being thrown off of the same.

It consists of the construction of the pedestals of the car whereby the wheels as 20 they change their angularity of the rails are prevented from abutting said pedestals and rubbing against the same which otherwise would prevent the wheels from rotating.

25 The invention is satisfactorily illustrated in the accompanying drawing, but the important instrumentalities thereof may be varied, and so it is to be understood that the invention is not limited to the specific 30 details shown and described, as long as they are within the spirit or scope of the claims.

Figure 1 represents a side elevation of a toy car embodying my invention.

Figure 2 represents a bottom plan thereof. 35 Figures 3 and 4 represent diagrammatic views partly in horizontal sections illustrating the running of the car on curved tracks.

Similar numerals of reference indicate corresponding parts in the figures.

40 Referring to the drawings,

1 designates the body of a toy car, and 2 designates the pedestals thereof, the latter having the axles 3 of the wheels 4 mounted therein, said wheels being adapted to run 45 on the curved rails 5 which may be for flat or spiral tracks as may be used for the toy. One member of each pair of pedestals has therein the cylindrical opening 6, and the other member thereof has therein the elongated slot 7, the opposite axles of a pair

of wheels occupying respectively said opening rotatably only therein and said slot both rotatably and slidably therein. Consequently as the wheels run on the curved rails and change their angularity thereon 55 the axles in the slots give and slide therein and the wheels thereof compensate for the curvature of the rails whereby when the car is running the axles are prevented from binding on the rails and jumping the rails 60 or being thrown off therefrom. Again, the inner faces of the slotted pedestals are deflected outwardly in horizontal direction in curved or bent form so that the outer sides of the wheels of the axles that occupy the 65 slots in the pedestals and change their angularity when running in conforming to the curvatures of the rails are prevented from being brought into contact with the inner sides of said pedestals as stops which would 70 otherwise interfere with the free running of the wheels as will be fully understood on reference to Figures 3 and 4.

The slots will be reversed on the pedestals according as the tracks are curved to the 75 right or left.

Having thus described my invention what I claim as new and desire to secure by Letters Patent, is:—

1. In a toy car, a body, wheels, an axle 80 for said wheels, and opposite pedestals on said body, one of said pedestals having therein a cylindrical opening for one end of the axle mounted rotatably therein, and the other pedestal having therein a horizontally extending elongated slot in which the other end of said axle is both rotatably and slidably mounted. 85

2. In a toy car, a body, wheels, an axle for said wheels, and pedestals, the latter being adapted to form the opposite bearings of said axle, one end of said axle being only rotatably mounted in its respective pedestal, and the other end thereof being rotatably and slidably mounted in its pedestal. 95

FREDERICK C. BAUER.
